LOUVERED BUILDING BLOCK

Lawrence S. Fulwider, 8569 Lamonto Ave. N.,
Jacksonville, Fla.

Filed Apr. 15, 1963, Ser. No. 74,445

Term of patent 14 years

(Cl. D18—2)

FIG. 4

FIG. 5

FIG. 2

FIG. 3

FIG. 1

FIG. 1 is a front elevational view of the louvered building block embodying my new design;

FIG. 2 is a rear elevational view of the louvered building block shown in FIG. 1;

FIG. 3 is a sectional view of the building block shown in FIG. 1 as seen along the lines 3—3 therein;

FIG. 4 is a top plan view of the louvered building block shown in FIG. 1; and

FIG. 5 is a side elevational view of the louvered building block shown in FIG. 1.

I claim:

The ornamental design for a louvered building block, substantially as shown.
